CLAIM

The ornamental design for wall mounted illuminable sign
for posters, as shown and described.

DESCRIPTION

FIG. 1 is a perspective view of a wall mounted illuminable
sign for posters showing my new design, with the broken
line showing for illustrative purposes only and forming no
part of the claimed design;

FIG. 2 is a top plan view thereof;

FIG. 3 is a front elevation view thereof;

FIG. 4 is a left side elevation view thereof;

FIG. 5 is a right side elevation view thereof;

FIG. 6 is a bottom plan view thereof; and,

FIG. 7 is a rear elevation view thereof.
